(57) **CLAIM**

I claim the ornamental design for the clipboard with storage container, as shown and described.

DESCRIPTION

FIG. 1 is a perspective view of a clipboard with storage container showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines in FIG. 1 are included for the purpose of showing a portion of the clipboard that forms no part of the claimed design.
